UNDERARM SLEEVE CONSTRUCTION

Joseph Clyne, Bronx, N. Y., assignor, by mesne assignments, to Flexsleev, Inc., a corporation of New York

Original application August 29, 1947, Serial No. 771,342, now Patent No. 2,583,089, dated January 22, 1952. Divided and this application June 9, 1951, Serial No. 230,786

3 Claims. (Cl. 2-93)

1

My invention relates to improvements in garments and more particularly to an improved jacket or coat construction in which the elements are combined in such a manner as to provide a normal fit for the wearer and at the same time provide a construction which will permit free movement of the arms and body of the wearer.

This application is a division of my pending application Serial No. 771,342, filed August 29, 1947, now Patent No. 2,583,089, for "Garment Construction," which in turn is a continuation-in-part of my applications, Serial No. 595,411, filed May 23, 1945, for "Garment" and Serial No. 627,009, filed November 6, 1945, for "Garment and Garment Construction," now Patents 2,426,818 and 2,426,819, respectively. Claims to divisible subject matter disclosed and claimed in my application Serial No. 771,342 are presented in the present application.

When a person wearing a jacket of common construction attempts to raise his arm, it is a common experience to find that the sleeve of the jacket places a strain on the upper arm muscle so that the wearer does not have free movement of his arm. Furthermore, it is a common experience to find that the wearer of an ordinary jacket cannot raise his arms without pulling the rest of his garment out of position, to either twist it around his body, or make it ride up. This is particularly true if the wearer of the garment is in a sitting position. In some cases, it is very difficult for one in a sitting position to raise his arms when wearing a jacket of ordinary construction. The strains produced on the arm muscles under such conditions necessarily make the wearer of the garment uncomfortable and gives him the feeling that his arms are held down under tension.

The primary object, therefore, of the present invention is to provide an improved garment construction which will overcome the difficulties and objections referred to above, and particularly to provide a jacket, coat, or other garment in which there is a minimum of restraint against free arm movement.

Another object of the invention is to provide an improved garment construction which permits raising of the wearer's arms without strain on his arm muscles and without pulling the rest of the garment out of its normal position.

A further object of the invention is to provide an improved garment construction which is adapted to permit the free swinging of the arms.

According to one form of the invention, the improved garment construction comprises a garment having a body portion and sleeves therefor

each sleeve comprising an under-arm portion, or under-sleeve section, and an over-arm portion, or top sleeve section, provided with end edges attached at the front of the body of the garment. 5 In this construction the attachment end portions of the sleeve differ from a standard sleeve but include an armpit allowance which is blended into its attachment end and gradually diminishes in width from the point where the two portions of the sleeve are attached to one another at the front of the garment, the end edge of the allowance of the under-arm portion including a wave curve of relatively small amplitude with the outwardly projecting portion of the wave curve positioned at the armpit of the garment, the over-arm portion of the sleeve having an attachment edge of outwardly curved symmetrical shape, the center of which is positioned at the shoulder of the garment.

The sleeves for the garment may be two-piece or one-piece sleeves which differ from standard or conventional sleeves by having the allowances described above.

The garment of the present invention is no more difficult to make than a standard garment, and may be manufactured without additional cost to the wearer.

Other features, objects and advantages of the improved jacket construction of the present invention will be apparent to those skilled in the art from the following more detailed description taken in connection with the accompanying drawings forming a part of this application.

In the drawings:

Fig. 1 is a broken view partly to one side, of a jacket constructed in accordance with the features of the present invention, illustrating the relationship between the sleeve structure and the body of the jacket, with the sleeve in raised position.

Fig. 2 is a pattern type view of the top and undersections of a two-piece sleeve according to the invention, as shown in Fig. 1, in which each section is provided with a compound allowance of particular configuration, the under-arm section including a substantial projection on its attachment edge.

Fig. 3 is a broken side view similar to that of Fig. 1, showing the appearance of a jacket made with a one-piece sleeve having the pattern shown in Fig. 4.

Fig. 4 is a pattern type view representing a combined under-sleeve and top sleeve including an integral allowance similar to the combined allowances of the two pieces shown in Fig. 2.

Referring to Fig. 1 of the drawings, this view shows a jacket constructed of suitable fabric in accordance with the present invention, from front and back body sections having a standard arm-hole, and under-arm and top or over-arm sleeve sections patterned the same as those shown in Fig. 2. In Fig. 1 the jacket comprises a front section 10 attached to a back section 12 by means of a seam 14 which extends to the armpit of the garment. The two back sections of the garment, of course, are attached to each other by a seam at the back of the jacket.

Each of the sleeves 16 of the jacket shown in Fig. 1 comprises an under-arm sleeve section 18 and a top or over-arm sleeve section 20, having the respective pattern shown in Fig. 2. These sleeve sections are attached to each other by a front seam 22 and a back seam 24. The sleeve 16 is attached to the armhole section of the front and back sections of the garment by means of a seam 26. The jacket of Fig. 1 includes a collar and other features which may be desired for a particular style.

The under sleeve section 18 of the jacket, as shown in Fig. 2, differs substantially from the standard sleeve pattern at the armhole section of the sleeve, the shape of the standard sleeve pattern where it differs from the sleeve section 18 being indicated by a dotted line 28. Therefore, according to the present invention, the under-sleeve section 18 includes at the armhole additional material or a compound allowance 29 integral with the sleeve section and of crescent shape, which is enlarged or wider toward the armpit section of the sleeve than at the back. This allowance includes an integral tail piece or extension 30 extending substantially along the front edge of the under-sleeve section. The armhole or attachment end of the under sleeve section 18 as modified by the allowance 29 therefore includes a substantially short edge extending from an edge 40, a projection 31 with two similar curves extending therefrom, one of which runs up to the short edge and the other to the edge 36. The curves and the projection 31 on the attachment edge of the under-arm section form a wave curve of relatively small amplitude. In this structure the edge 36 is nearly as long as the edge 40 so that when the arm is raised there is ample material at the armpit to give freedom of arm movement.

The top sleeve section 20 as shown in Fig. 2 also differs from the standard pattern which is indicated by the dotted line 32. This section of the sleeve therefore includes a substantial allowance at the armpit and along the lower edge 38 of the sleeve section which is integral with the material of the sleeve. This allowance has a double wing-shaped configuration, one wing of which, 34, extends from the front edge 38 of the sleeve along the attachment edge while the other wing, 35, extends substantially along the front edge 38 of the sleeve from the armpit section. The allowances 34 and 35 make the shoulder portion of the top sleeve 20 substantially symmetrical and the edges 38 and 42 substantially equal, the end attachment edge comprising a rather gentle convex curve, the center of which is attached at the shoulder of the garment.

In making up the sleeve of the jacket shown in Fig. 1 from the sleeve sections 18 and 20 shown in Fig. 2, edge 36 is attached to edge 38 by means of a seam to form the seam 22 shown in Fig. 1, while edge 40 of the under-sleeve section 18 is attached to the edge 42 of section 20 to form the seam 24.

When the sleeve sections 18 and 20 are sewed together, the tail or wing allowance 30 is sewed to the wing allowance 35, and the ends of the allowances 29 and 34 are also sewed together since they comprise a portion of the edges 36 and 38. The allowances 30 and 35 serve to provide a sleeve having an armpit section which is slightly larger than the standard sleeve, but the allowances 29 and 34 provide a sleeve which gives the wearer freedom to swing his arms and raise them in any position without having his arm muscles placed under any sleeve strain or tension. After the sleeve sections shown in Fig. 2 are assembled as described above the sleeve is sewed to the body of the garment with the projection 31 at the armpit of the garment and the center of the attachment edge of the section 20 at the shoulder of the garment. The illustration in Fig. 1 shows the appearance of the sleeve in raised position when the sleeve sections include the allowances shown and described in detail in connection with Fig. 2 of the drawings.

Fig. 3 shows a garment having a style similar to that of Fig. 1, but which is provided with a one-piece sleeve having the pattern shown in Fig. 4. The garment shown in Fig. 3 comprises a front section 44 attached to a back section 46 by a seam 48, and a one-piece sleeve 50 attached to the body of the garment by a seam 52. The sleeve has a single lengthwise seam 54 corresponding generally to the seam 24 in Fig. 1.

The one-piece sleeve structure shown in Fig. 4 comprises a combination of an under-and-top sleeve similar to those shown in Fig. 2. In Fig. 4 the dotted line 58 represents the outline of the standard sleeve pattern where it differs from that of the sleeve 50. The sleeve 50 includes a substantially symmetrical generally crescent-shaped armpit allowance 58 having an enlarged central body section and side sections which terminate substantially at a point. This structure, including a projection 60, gives a low wave curve for the armpit attachment edge in place of the usual deep valley, to provide a gentle slope into the large shoulder curve 52. The use of this sleeve results in a garment in which there is only one seam 54 in the sleeve, at the back, formed by sewing together edges 64 and 66, and in which the allowance 58 gives ample freedom for lifting the arm.

While it will be apparent to those skilled in the art that various types of garments may be made in accordance with the invention, it may be pointed out that the forms shown in the drawings are particularly adapted for use in connection with men's and ladies' jackets. In this connection it is to be understood that the improved garment construction may be employed in various types of apparel including ladies' waists, men's shirts and other apparel.

The improved garment construction of the present invention results from a combination of relatively simple structural features which give the garment a sleeve and armpit structure permitting free movement of the wearer's arms without distorting the garment and without binding the arm muscles. A wearer of the garment of the present invention may raise his arms in any position without breaking the sleeve or pulling the body of the garment out of its normal position. From the foregoing description, it will be apparent that certain variations may be made in the structure of the garment and still achieve the objects of the invention. Such changes are contemplated as coming within the spirit and scope of the invention.

I claim:

1. In a garment, a body portion, and a sleeve having an under-arm portion and an over-arm portion, said portions having edges attached together along the front of the sleeve, each portion of the sleeve having an attachment end attached to the body portion of the garment at the armhole, each of said portions of the sleeve including an armpit allowance which is blended into the attachment end of the sleeve and gradually diminishes in width from where the two portions are attached to one another at the front, the end edge of the allowance of the under-arm portion including a wave curve of relatively small amplitude with the outwardly projecting portion of the wave positioned at the armpit of the garment, said over-arm portion having an attachment edge of outwardly curved symmetrical shape the center of which is positioned at the shoulder of the garment.

2. A garment as defined in claim 1 in which the attached edges along the front of the sleeve each include a longitudinal allowance which extends from the allowance adjacent the attachment end of the sleeve and gradually diminishes in width toward the free end of the sleeve.

3. In a garment, a body portion, and a sleeve having an under-arm portion and an over-arm portion, said portions having edges attached together along the front of the sleeve, each of said

5

15

portions having an end edge attached to the edge of the armhole of the body of the garment, the attachment end edges of said portions merging with each other by a gentle curve, each of the attachment end portions of the sleeve including an armpit allowance which is blended into the attachment end of the sleeve and gradually diminishes in width from where the two portions are attached to one another at the front, the end edge of the allowance of the under-arm portion including a wave curve of relatively small amplitude with the outwardly projecting portion of the wave positioned at the armpit of the garment, said over-arm portion having an attachment edge of outwardly curved symmetrical shape the center of which is positioned at the shoulder of the garment.

JOSEPH CLYNE.
